UNITED STATES PATENT OFFICE

2,603,116

SPIRAL ACTUATED SLIDABLE JAW
END WRENCH

Guido F. Schlotte and Richard C. Winter, Milwaukee, Wis., assignors to De Pere Tool Products, Inc., De Pere, Wis., a corporation of Wisconsin

Application May 12, 1950, Serial No. 161,568

4 Claims. (Cl. 81—165)

1

This invention relates to an improved construction of adjustable end wrench and has for its primary object to provide a wrench construction which may be much more economically manufactured and sold due to certain novel features of construction thereof whereby otherwise necessary drilling of holes, broaching of head contour and other manufacturing operations are eliminated and by means of which otherwise necessary internal bearing surfaces or end journals may be omitted without adversely affecting the operation of the tool.

A further object of the invention is to provide an end wrench wherein the use of beveled gears is eliminated and which is so constructed that one of the gears of the wrench provides its own bearing surface.

Various other objects and advantages of the invention will hereinafter become more fully apparent from the following description of the drawing, illustrating a presently preferred embodiment thereof, and wherein:

Figure 1 is a side elevational view of the wrench;

Figure 2 is an edge elevational view thereof looking from top to bottom of Figure 1;

Figure 3 is a longitudinal sectional view taken substantially along a plane as indicated by the line 3—3 of Figure 2, and

Figures 4, 5 and 6 are enlarged cross sectional views taken substantially along planes as indicated by the lines 4—4, 5—5 and 6—6, respectively, of Figure 3.

Referring more specifically to the drawing, the adjustable end wrench in its entirety is designated generally 8 and includes mating sections, designated generally 9 and 10, having complementary portions combining to form a wrench head 11 and a handle 12.

The mating sections 9 and 10 preferably constitute drop forgings which are copper-brazed together along their abutting faces 13 (Figures 4, 5 and 6). The handle portions and the sections 9 and 10 are recessed to provide a relatively large bore 14 which extends from adjacent the head and which opens outwardly of the end of the handle, disposed remote to the head 11. The sections 8 and 9 are recessed to provide a bore 15 in the head 11 which is disposed obliquely to the axis of the handle 12 and which is closed at one of its ends by a restricted frusto-conical end of the bore 15 which forms a journal 16 and which has an opposite open end which is internally threaded as seen at 17. The bore 14 and the bore 15 are connected by a bore 18 which constitutes

2

an enlarged extension of the inner end of the bore 14 and which is formed by reaming out complementary portions of the sections 9 and 10; said enlarged bore portion 18 forming a bearing or journal, as will hereinafter be described. The edge of the head 11, remote from the handle 12, is recessed as seen at 19 to form a stationary jaw 20 which constitutes an integral part of the head 11 and which is disposed remote from the handle 12 and extends at an oblique angle away from said handle. The mating head portions are provided with complementary recesses forming a passage 21 which extends parallel to the bore 15 and which has a side portion 2 opening laterally into the bore 15 and an opposite, restricted side portion 23 which opens outwardly of the head through its recessed edge 19, as best illustrated in Figure 3.

A brass bushing 24 is detachably secured in the bore 12, adjacent the end thereof remote from the head 11, by a setscrew 25 which extends into the bore 14 through a threaded opening 26 and which bears with its inner end against a portion of the bushing 24. A strip of metal is spirally wound to form a spiral 27 the convolutions of which are spaced apart to form a spiral slot 28 therebetween. A stem 29 has one end disposed in an end of the spiral 27 and is suitably secured thereto as by a soft solder connection; the opposite end of the stem 29 extending from said end of the spiral 27 through the bore of the bushing 24 and in which the stem is journaled to rotatably support said end of the spiral. Said last mentioned portion of the stem 29, adjacent its terminal, is provided with annular grooves 30 in which a spring retaining clip 31 is detachably engaged. Said clip 31 bears against the outer side of the bushing 24 to prevent the stem 29 from sliding through the bushing inwardly of the bore 14 and the end of the spiral 27 in which the stem 29 is secured bears against the opposite side of the bushing 24 to prevent the stem from sliding therethrough in the opposite direction. The handle sections are preferably provided with aligned openings 32 located beyond the bushing 24 to afford more ready access to the spring clip 31.

A brass gear 33 is journaled in the enlarged bore portion 18. A peg 34 has one end secured in the gear 33, centrally thereof, and projects perpendicularly from said gear into the bore 14 and is received in the opposite end of the spiral 27 which is similarly secured by a soft solder connection to said peg 34 and so that said end of the spiral 27 will abut against an inner end of the gear 33 from

which the peg 34 projects. The opposite outer end of the gear 33 which faces into the bore 15 is internally beveled or recessed, as seen at 35 so that the teeth of the gear 33 at said outer end substantially correspond to a crown gear or wheel.

A worm 36 is loosely disposed in the bore 15 and the stem or core 37 of said worm has a frusto-conical end 38 which extends beyond one end of the spiral or thread 39 of the worm and which frusto-conical end is journaled in a similarly shaped closed end 16 of the bore 15. The stem or core 37, beyond the opposite end of the thread 39 is provided with a toothed enlargement forming a pinion 40 which is disposed to mesh with the ends of the teeth of the gear 33 which are contiguous with the recessed or internally beveled end 35 of said gear. Beyond the pinion 40, the stem or core 37 is of reduced diameter and provided with a tapered terminal 41 which is journaled in a similarly shaped recess 42 formed in one end of an externally threaded thrust bearing 43 which threadedly engages the threaded bore portion 17. An externally threaded annular member 44 engages the threaded bore portion 17, outwardly of the bearing 43 to retain said bearing in an adjusted position in the bore portion 17 and so that the pinion 40 will be properly disposed for meshing engagement with the gear 33.

A movable jaw 45 has a shank 46 which slidably engages in the passage 21 and which has a restricted side edge portion 47 at one end thereof which is provided with teeth for engaging the worm thread 39. The shank 46 has a recessed side edge portion 48 at its opposite end to accommodate the bearing 43 and the threaded member 44. The other side edge 49 of the shank 46 is likewise reduced in thickness to slidably fit the reduced recess portion 23 and the jaw 45 is integrally formed with said reduced shank portion 49 and extends laterally therefrom at the end of the shank remote from its toothed portion 47 so that the jaw 45 is disposed in opposed relationship to the stationary jaw 20 for movement toward and away from said jaw 20 when the shank 46 is reciprocated in the passage 21.

The handle 12 is preferably oval-shaped in cross section, as seen in Figures 4, 5 and 6 and a similarly shaped collar 50 is slidably disposed thereon and has a pin 51 fixed thereto and which projects inwardly from a portion thereof through a longitudinally extending slot 52 formed in the part of the handle 12 formed by the section 10. The inner end of the pin 51 loosely engages in the spiral slot 28 of the spiral 27 so that by sliding the collar 50 in one direction on the handle 12 the spiral 27 and the gear 33 which is secured thereto will be revolved in one direction, and by sliding the collar in the opposite direction, the spiral and gear will be revolved in the opposite direction. It will be readily apparent that through meshing engagement of the gear 33 and pinion 40, the worm 36 will be revolved in unison with the spiral 27 so that when said worm is turned in one direction the shank 46 will slide in the passage 21 in one direction and when the worm is revolved in the other direction, said shank 46 will be moved in the opposite direction thereby causing the movable jaw 45 which is carried by the shank 46 to be moved either toward or away from the stationary jaw 20.

It will thus be apparent that an adjustable end wrench of extremely simple construction has been provided which is capable of being very economically manufactured due to the fact that the sections 9 and 10 of the body member 8 may be pre-

formed with proper recesses therein to form the bore 14, enlarged bore 18, the bore 15 and passage 21, when said sections are secured together in abutting engagement by copper-brazing, as previously described. Obviously, the flat surfaces of the sections 9 and 10 are smoothly ground before the sections are connected thereby greatly facilitating the operation of finishing the body member. Likewise, this construction eliminates the need for a thrust bearing to hold the gear 33 against displacement toward the head 11 thereby greatly simplifying the operation of constructing the body member 8 and eliminating the need to use beveled gears. This is accomplished by the stem 29 and spring clip 31 which combine with the bushing 24 to prevent the spiral 27 and gear 33 from being displaced longitudinally of the handle 12 in response to the force exerted on the spiral 27 by the pin 51.

Various modifications and changes are contemplated and may obviously be resorted to, without departing from the spirit or scope of the invention as hereinafter defined by the appended claims.

We claim as our invention:

1. An adjustable end wrench comprising a body member having one end forming a wrench head and an opposite, elongated end forming a wrench handle, a fixed wrench jaw formed integral with said wrench head, said wrench head being recessed to provide an internal recessed portion, a movable jaw having a shank slidably engaging in the recessed portion and reciprocably movable therein for moving said movable jaw therewith toward and away from the stationary jaw, a worm journaled in the recessed head portion, said shank having a toothed portion engaging the worm for moving said shank in the recessed head portion when the worm is removed, said handle having a bore extending longitudinally therethrough having one end opening into the recessed head portion, a helically wound strip loosely disposed in the handle bore forming a spiral having spaced convolutions, said handle having a longitudinally extending slot, a collar slidably disposed on the handle, a pin extending inwardly from the collar loosely through said slot and engaging between adjacent convolutions of the spiral to revolve the spiral in opposite directions when the collar is reciprocated on the handle, a gear secured to one end of said spiral and journaled in an end of said bore and extending partially into the recessed portion of the head, a pinion secured to the worm and meshing with said gear, said gear and pinion being disposed at an acute angle, and means journaling and non-slidably supporting the end of the spiral located remote from said gear adjacent the end of the handle remote from the head.

2. An adjustable end wrench as in claim 1, said means comprising a bearing detachably secured in the handle bore, a spindle having one end secured in the last mentioned end of the spiral and having a portion extending through and journaled in said bearing, and a member detachably connected to the opposite end of said spindle and engaging the side of the bearing opposite to the side thereof engaged by the last mentioned end of the spiral to combine with said last mentioned spiral end to retain the spiral and gear against reciprocating movement in the handle bore in response to the thrust exerted on the spiral by the collar supported pin.

3. An adjustable end wrench as in claim 1, said handle bore having a portion of enlarged

diameter opening into the recess of the head in which said gear is journaled, said gear having a recessed end facing toward the worm whereby the ends of the gear teeth facing toward the worm form a crown gear for meshing engagement with the worm pinion.

4. An adjustable end wrench as in claim 1, said body member being formed of complementary sections having recessed complementary sides, said recessed sides being permanently secured together in abutting engagement to form the head recess and handle section bore.
